[57] CLAIM

The ornamental design for an identification label, as shown and described.

DESCRIPTION

FIG. 1 is a top plan view of an identification label showing my new design;

FIG. 2 is a side elevational view thereof, the opposite side being a mirror image thereof;

FIG. 3 is a bottom plan view;

FIG. 4 is a right end elevational view;

FIG. 5 is an enlarged scale fragmentary cross-sectional view taken along 5—5 of FIG. 1; and

FIG. 6 is an enlarged scale cross-sectional view taken along line 6—6 of FIG. 2.

The pattern shown fragmentarily on the strap in FIGS. 1, 3 and 4 is understood to be continuous along the entire length of the strap.

FIG. 1.

FIG. 2.

FIG. 3.

FIG. 5.

FIG. 6.

FIG. 4.
